(57) **CLAIM**

The ornamental design for a “sump pump”, as shown and described.

DESCRIPTION

FIG. 1 is a perspective view of the top, front and left side of the sump pump;

FIG. 2 is a front elevation view of the sump pump;

FIG. 3 is a right side elevation view of the sump pump;

FIG. 4 is a rear elevation view of the sump pump;

FIG. 5 is a left side elevation view of the sump pump;

FIG. 6 is a top plan view of the sump pump; and,

FIG. 7 is a view looking upwardly at the sump pump from below.

The broken-lines of FIGS. 1 through 7 depict cords, fasteners, a rib adjacent to a handle at the top portion of the pump, and a pair of recesses on the rearward side of the pump. These broken line features are depicted for illustrative purposes only, and form no part of the claimed design.
